CONCRETE WALL FORM

Joseph J. Pirz, Flushing, N. Y.

Application October 30, 1946, Serial No. 706,640

4 Claims. (Cl. 25—131)

1

This invention relates to form walls for pouring concrete.

An important object of my invention is to provide form wall sections of unit type construction which can be assembled to produce walls of various dimensions and proportions, and which can be repeatedly used on successive jobs.

The form wall sections, which may be in the shape of panels of plywood, metal or other structural material, preferably of rectangular or square outline, are provided with reinforcing and protective edging strips or angles which provide projecting metal flanges by which adjacent sections may be secured together. In this way, by joining section to section, both horizontally and vertically, a wall of desired length and height can be erected. To provide for the maintenance of two walls in parallel relation at the proper distance apart for the pouring space, each section is perforated at uniform intervals along each of its four edges for the reception of tie rods or wires of uniform predetermined length which extend through the panel and reinforcing strips and across the intervening space between the two walls. These tie wires, when locked in place, serve as distance pieces for the two walls. The projecting flanges of the wall sections are provided with transverse slots which register with those of adjacent continuously contactive flanges to receive loops of wire deflected transversely from the projecting ends of the tie wires by which the adjacent sections are secured together and the spacing of the two walls accurately fixed.

The principles of the invention are illustrated by way of example in the accompanying drawing, in which:

Figure 1 is a detail perspective view of portions of adjacent wall sections of the two opposite walls, showing the tie wires in successive stages of connection with the walls.

Figure 2 is a plan view, partly in horizontal section and with parts broken away, of a combined flange-engaging and wire-bending implement applied to adjacent projecting flanges of two adjacent wall sections, the locking jaws being shown in open position and the wire-bending plunger in normal position.

Figure 3 is a similar view of the same parts with the locking jaws closed and the wire-bending plunger in shifted position.

Figure 4 is a detailed sectional view through the parts shown in Figure 3, the section being on the line 4—4 of Figure 3, and

Figure 5 is a cross section through adjacent

2

portions of two wall section having a modified form of reinforcing strips secured thereto.

Referring to Figure 1 of the drawing, I have here shown in perspective view, with parts in section, the general relationship of the panels and reinforcing strips of the wall sections and the tie wires extending between two parallel walls. Each wall section has a panel 10 reinforced and protected along its edges by reinforcing strips 11 suitably secured thereto. The panels 10 may be of, for example, plywood, and the reinforcing strips of steel. The reinforcing strips are preferably of angle iron section to provide base flanges 11 and projecting flanges 12, as shown in Figures 1 to 4 inclusive, or they may be of T-section as illustrated in Figure 5. In Figure 5, the base flange 13 of the reinforcing strip has the inwardly extending flange 14 and the projecting flange 15. The base flange 13 and the inwardly extending flange 14 are secured to the panel 10 by suitable screws 16 and 17. The projecting flanges 12 (Figure 1) are provided with transverse slots 18 to receive the wire loops 19 formed on the projecting ends of the tie wires 20, as will be hereinafter explained. Similar slots 21 are formed in the projecting flanges 15, as shown in Figure 5, for a similar purpose. These slots 18 of the projecting flanges 12 are distributed at uniform spacing along each projecting flange in registration with perforations 22 of the base flanges 11. Perforations 22 extend through the panels 10 to receive the tie wires 20 which extend across the space from one wall to the other. It will be understood that similar provision is made in the base flanges and panels of the construction shown in Figure 5. The slotted projecting flanges of the reinforcing strips are provided with perforations such as shown at 23 in Figure 1, in fixed and uniform spacing with respect to the slots, for a purpose which will be described.

For the purpose of securing the tie wires 20 in the wall sections, my invention provides an implement having jaw sections by which it is locked on the projecting flanges, and a wire-bending plunger to deflect a portion of the projecting ends of the tie wires transversely into and through the slots of the projecting flanges. Figures 2 to 4 show an illustrative embodiment of such an implement. This implement comprises a main body portion 24 on which are mounted the operating parts of the flange-engaging and wire-bending members. Extending rigidly from this main body 24 is a hand lever or arm 25 which is grooved or recessed at 26 to receive a toggle

link 27, and at 28 to receive a flange-engaging jaw member 29. One end of the link 27 is pivoted to the arm 25 at 30, and the jaw member 29 is pivoted to the arm at 31. The jaw member 29 is a T-section at its gripping face 32, and is slotted at 33 to receive the cross pin 34 of its actuating lever 35, which lever is bifurcated or forked at the end to embrace the jaw member. An adjustable screw 36, threaded in the boss or enlargement 37, extends into the slot 33 to provide an adjustable limit stop. The toggle link 27 is connected with the actuating lever 35 by means of a fulcrum pin 38, the link being disposed in a groove or recess 39 formed in the lever 35. The lever system described constitutes a toggle for actuating and locking the jaw member 29 upon one face of a projecting flange 12 of the reinforcing strip, against the pressure of the opposing main body portion 24 of the implement, which engages the opposite face of an adjoining projecting flange 12, as can be seen in Figures 2, 3 and 4. The adjusting screw 36 can be turned to compensate for any irregularities, or to take up wear, so that the toggle can be swung through the dead center into and out of locking position. To ensure the application of the implement in proper relation with respect to the slot 18 and perforation 22, the main body 24 may be fitted with a registering pin 40 which enters one of the perforations 23 in the projecting flange portion 12 of the reinforcing strip. Figure 4 illustrates a second registering pin 41 which may be mounted in an extension 42 of the main body 24 to seat in another of the perforations 23 of the projecting flange portion 12 of the reinforcing strip.

The body portion 24 of the combined flange-engaging and wire-bending implement has a groove 43 extending across its flange-engaging face to receive and guide the tie wire 20. This groove 43 terminates in a wall 44 which serves as a stop or abutment for the projecting end of the wire 20. Beneath this groove 43, the body portion 24 is chambered at 45 to receive a plunger 46 carrying a bending die 47 whose outer end is concave to embrace the wire 20 immediately adjacent the registered slots 18 of the projecting flanges 12 of two adjacent reinforcing strips. Actuation of the bending plunger 46 toward the slots 18 from the normal position shown in Figure 2 to the position shown in Figure 3 deflects a portion of the wire 20 into the form of a loop which projects through the slots 18 where it can be secured by a wedge pin 48, as shown in the lower portion of Figure 1. To actuate the plunger 46, I prefer to employ a rack and pinion such as illustrated in Figure 4. Thus the plunger 46 is formed with the teeth 49 engaged by the teeth of pinion 50 fixed on an operating shaft 51 which projects from the body portion 24 and is fitted with an operating lever 52. A journal plate 53 surrounding the shaft 51 may be secured by screws 54 to the face of the body portion 24. This plate has a collar 55 which abuts against the pinion 50 to hold the latter in its proper position.

The plunger 46 has a lug 56 projecting rigidly from one side thereof and perforated to receive a rod 57. This rod has a roughened, wire-gripping end 58 projectable into the groove 43 through an aperture of the main body portion 24. This rod 57 is provided with a collar 59, beneath which is disposed a coil spring 60, which latter is confined between the collar 59 and the perforated lug 56. Another collar 61 may be mounted on

the opposite end of the rod to engage the lug 56 for the purpose of retracting the rod 57 when the wire-bending plunger 46 is retracted, so as to be out of the way of a tie wire being inserted. It will be apparent that after the tie wire has been placed in position upon its guiding groove 43, the rod 57 will be resiliently urged toward the tie wire as the plunger 46 is actuated, thus gripping the tie wire and holding it securely against displacement of its intermediate portion while its projecting end is being bent into the loop form shown in Figure 3.

Referring first to Figure 1 of the drawing, it will be understood that a tie wire 20 of predetermined, standard length, corresponding with the desired spacing of the form walls, is extended across from one wall section to the other with its ends projecting, as clearly shown in the upper portion of this figure. This wire may be inserted either before or after the flange-engaging and wire-bending implement is placed on the adjacent flanges 12, as shown in Figure 2, and locked thereon, as shown in Figure 3 of the drawing, by actuating the lever 35 of the toggle. With the parts in this position, the operating lever 52 of the bending mechanism is actuated to move the bending plunger 46 from the position shown in Figure 2 to the position shown in Figure 3. It will be seen that the rod 57 first resiliently engages and locks the intermediate portion of the tie wire 20, after which the continued movement of the plunger 46 causes the bending die 47 to force a single loop of wire 19 through the slots 18 of the continuously contacting projecting flanges 12. The performance of this operation at the two ends of each tie wire 20 fixes the spacing of the wall sections on opposite sides of the pouring space. The operating lever 52 is then returned to normal position and a wedge pin 48 inserted in each loop of wire 19 to prevent its escape. The combined flange-engaging and wire-bending implement may then safely be removed and shifted to a new position for operating on another tie wire. As long as the wedge pins 48 remain in place, the wires hold the adjacent wall sections together, in which position they remain until the concrete has been poured and allowed to set. After the concrete has set, the wedges are removed to permit the separation of the sections from each other. By cutting off the projecting ends of each wire, the form sections through which they pass can be removed from the finished concrete wall for use on a subsequent job.

I claim:

1. A concrete form comprising in combination a pair of form walls, each wall made up of unit sections assembled edge to edge, each section comprising a panel and an apertured reinforcement flange projecting from the edge thereof, and tie wires extending across the pouring space and projecting through opposite sections of the two walls, the projecting end of each tie wire extending in a single loop through registering apertures of adjacent continuously contactive projecting flanges of adjoining sections and secured therein to secure the sections together and to space said form walls.

2. A concrete form comprising in combination a pair of form walls, each wall made up of unit sections assembled edge to edge, each section comprising a panel and a reinforcement strip of angular section having a perforated base flange secured to the panel and an apertured projecting flange extending outwardly therefrom, and tie

wires extending across the pouring space and projecting through perforated base flanges of opposite sections of the two walls, the projecting end of each tie wire extending in a single loop through registering apertures of adjacent projecting flanges of adjoining sections and secured therein to secure the sections together and to space said form walls.

3. A concrete form comprising in combination a pair of form walls, each wall made up of unit sections assembled edge to edge, each section comprising a panel and an apertured reinforcement flange projecting from the edge thereof, tie wires extending across the pouring space and projecting through opposite sections of the two walls, the projecting end of each tie wire being transversely looped in a single loop through registering apertures of adjacent continuously contacting projecting flanges of adjoining sections, and wedge pins inserted in the projecting loops of the tie wires to secure the sections together and to space said form walls.

4. A concrete form comprising a pair of spaced

form walls, each wall being made up of a plurality of unit sections assembled edge to edge, each section comprising a panel and an apertured reinforcement flange projecting from each edge thereof, in combination with tie wires extending across the pouring space between said form walls and projecting through opposite sections of the two walls, the projecting ends of each of said tie wires being looped in a single loop through registering apertures of adjacent continuously contacting projecting flanges of adjoining sections and secured therein to hold said sections together and to space said form walls.
